CLAIM

We claim the ornamental design for a mounting plate, as shown and described.

DESCRIPTION

FIG. 1 is a front perspective view of the mounting plate; FIG. 2 is a rear perspective view of the mounting plate of FIG. 1;

FIG. 3 is a front view of the mounting plate of FIG. 1;

FIG. 4 is a rearview of the mounting plate of FIG. 1;

FIG. 5 is a side view of the mounting plate of FIG. 1;

FIG. 6 is a side view of the mounting plate of FIG. 1 taken 90° from the view in FIG. 5; and,

FIG. 7 is a cross section view of the mounting plate of FIG. 1 taken along line 7-7 of FIG. 3.

(Continued)

The ornamental design which is claimed is shown in solid lines in the drawings.

The broken lines in the drawings illustrate portions of the mounting plate and form no part of the claimed design.

1 Claim, 6 Drawing Sheets
